United States Patent Office

Des. 223,224
Patented Apr. 4, 1972

223,224

HOLDER FOR SEWING MATERIAL OR THE LIKE

Margaret A. Wilbrecht, 400 Carlotta,
Newport Beach, Calif. 92606

Filed July 29, 1970, Ser. No. 24,170

Term of patent 14 years

Int. Cl. D6—99

U.S. Cl. D3—19

FIG. 1 is a side perspective view of a holder for sewing material or the like showing my new design;

FIG. 2 is a front elevational view thereof on a reduced scale;

FIG. 3 is a side elevational view;

FIG. 4 is a rear elevational view;

FIG. 5 is a top plan view; and

FIG. 6 is a bottom plan view.

I claim:

The ornamental design for a holder for sewing material or the like, substantially as shown and described.
